UNITED STATES PATENT OFFICE.

JAMES H. MUNRO, OF PEN ARGYL, PENNSYLVANIA.

COVERING.

1,250,622.

Specification of Letters Patent. Patented Dec. 18, 1917.

Application filed March 13, 1912, Serial No. 683,556. Renewed May 14, 1917. Serial No. 183,590.

To all whom it may concern:

Be it known that I, JAMES H. MUNRO, of Pen Argyl, Pennsylvania, have invented certain Improvements in Coverings, of which 5 the following description, in connection with the accompanying drawings, is a specification, like characters on drawings designating like parts.

This invention relates to coverings for 10 roofs and other surfaces, and is of special utility when embodied in the construction of covering units possessing some of the properties of roofing tiles, as for example the ease with which they may be handled, their 15 durability, and their weatherproof and fire-proof qualities, but of much less weight for a given area of surface covered, and less expensive to manufacture and to lay, my improved covering being also less destructible, 20 and more capable of conformation to the contour of the surface on which my improved units are to be used, it being understood that I contemplate their utilization in any field for which they are adapted by their 25 nature.

Accordingly, an important object of my invention is to provide a covering having heatproof and fluid-proof elements, of which the fluid-proof element shall be so protected 30 by the heat-proof element that it will not be subject to destructive action by the weather or a high degree of heat, and so may be constituted of material of an oleaginous character, and therefore specially 35 qualified to exclude rain and other fluids from the surface covered, my present invention constituting a development of and improvement over, that disclosed in my Letters Patent No. 967,542, granted August 16, 40 1910, and to which reference may be had for the general problem involved.

To accomplish, therefore, my primary object of providing a covering having a substantially continuous, flexible surface of 45 heat-proof, wear-resisting material conforming closely in detail with the contour of its support, and protecting permanently from atmospheric effects a waterproofing element, I prefer to utilize an artificial stone or concrete comprising such materials as Portland 50 cement, with granular or gritty material such as coarse sand, granulated stone or other mineral substance, and I prefer to mold the aforesaid concrete in the form of 55 an extended sheet or unit which can be

rolled up for convenience in storage and installation, and preferably the refractory material will be formed on one or both sides of a layer of oleaginous cement, such as asphalt, which may be combined in any suitable 60 manner with the refractory layer, either alone or carried by a suitable vehicle, as for example a suitable fabric, such as burlap, or a fibrous material which holds the concrete in unit form, whether as a backing or an intermediate stratum. Fibers of like suitable material may be used in place of a woven fabric, the fibers preferably entering the cement layer or layers at their free ends, and being permeated by the asphalt, so that the 70 latter forms a continuous waterproof layer, co-extensive with the covering.

Whatever the material, I prefer in general to form each unit with a substantially continuous surface, although, as a modification, 75 it may if desired be weakened by scoring, or otherwise, either in longitudinal or transverse directions, or both, so that when laid it can be readily broken and deformed to fit the contour of its support, but ordinarily 80 will lie flat, and, when so formed, this cross-scoring serves also the double purpose of dividing the surface above into tessellæ pleasing in appearance and affording a safe tread for foot traffic, while, if desired, cross-scorings of the under surface may be provided, to furnish channels to distribute along 85 the lines of weakness, into position to heal the fractures, a certain portion of the excess of pitch or other bedding cement, if such a 90 bedding be provided, although my improved covering may be nailed or otherwise fastened directly to its support.

Among the most important objects of my invention, and one which effects a notable 95 advantage in the construction of my improved covering, is that the units may be manufactured at a distance from their installation, out of cement which can be seasoned in a suitably damp environment, so 100 that it is not liable to shrink and crack in place on the surface to be covered, a factor which has practically debarred concrete from successful use heretofore, when applied in bulk.

A cognate object of my invention, realized by this manufacture under favorable conditions, is to provide for the use of high-grade asphalt or pitch, of a high melting point preferably applied at the factory by experts 11

in the construction of the covering material, and at a suitable temperature, so that when the covering shall have been delivered for installation, the workmen required for its emplacement may be of the type ordinarily available everywhere, since the completed covering can be set in place as already indicated, or laid in a bed of pitch swabbed on the surface to be covered as emplacement proceeds.

Still another important object of my invention is to provide a laminated covering built up of laminae of Portland cement concrete preferably united by one or more layers of cement such as Portland cement applied in a plastic condition.

The various features of my invention will be illustrated and described fully in the accompanying drawings and specification and pointed out in the claims.

In the drawings, Figure 1 is a fragmentary view, in perspective, of portion of a covering in the construction of which my invention has been embodied;

25 Figs. 2 and 3 are respectively fragmentary views in plan and elevation respectively, illustrating a mode of scoring the covering to facilitate transverse deformation of the covering;

30 Figs. 4, 5 and 6 respectively are views in vertical section illustrating portions of coverings embodying my invention in various arrangements.

In the embodiment of my invention selected for illustration and description to enable ready and complete understanding of my improvements, the part designated by the reference numeral 1 is a layer of stonelike material of any suitable composition, 40 one convenient substance comprising a concrete containing Portland cement with a granular or gritty ingredient 2 such as coarse sand, the extent and thickness of this layer in each installation being suited to the exigencies of the particular installation.

45 For roof coverings I prefer to form the layer 1 rather thin, and extended in sheets or strips each of sufficient area to cover a substantial proportion of the roof, and when so formed I prefer to provide a suitable vehicle such as fibers 3, which may be in woven or felted form, or sown through or upon the surface of, the concrete at the time of its formation, the fibers entering and binding together the concrete, whether the same be in a single layer or a plurality of layers.

50 In Fig. 1 the fibers 3 are shown as forming part of a fabric 4 such as burlap, which may be loaded with a suitable waterproof substance, such as asphaltum or other oleaginous flexible cement indicated by the reference numeral 5, and in combination with the above, or in place of it, a layer or stratum 6 of waterproofing may be provided, as for example by coating the concrete at

the time of manufacture, or by swabbing the foundation with the layer 6 (see Fig. 5) or both coating the concrete and foundation 7 the coatings uniting to form a unitary layer 6.

70 The coating on the concrete may be of high-melting asphalt, applied by experts at the factory where the concrete layer 1 is made, and will preferably be so applied to insure permanency, and the bedding coating may be applied by less experienced workmen on the job, and use there may be made not only of high-melting asphalt, which is of course preferable where the conditions of weather and labor warrant such use, but also a low melting asphaltum or pitch may be utilized where found more convenient, as it is thoroughly protected by the refractory, stonelike, heatproof layer 1, in accordance with my invention.

75 An object of notable importance is to provide the layer 1 of stonelike character by manufacturing and seasoning it under damp conditions suitable to render it hard and unshrinkable, so that it constitutes virtually a stone veneer, wearproof and heatproof.

80 This layer 1 may be fractured by intention or accident in laying or in use, and is thus deformable to enter into conformity 95 with the contour of the roof or other surface 7 covered, but its fluidproof properties are not impaired by such fractures, which are healed, as indicated at 8, by the fluidproof stratum, and thus my improved 100 covering affords a substantially continuous, stonelike prepared material for roofing and analogous purposes, deformable transversely and capable of emplacement in units of substantial area.

105 To facilitate this deformation, if it be desired, for example, to roll up the units for transportation, the sheets or strips 1 may be scored transversely in one direction as at 9 in Figs. 2 and 3, or in the other direction 110 as at 10, either or both, and on one or both sides, in accordance with the exigencies of diverse situations.

115 Wherever possible, I prefer to preserve the surface unbroken, in order to reduce to a minimum all solution in the continuity of the heatproof and wearproof element.

In Fig. 5 I have shown a layer 1 of stonelike material constructed substantially as illustrated in Fig. 1, laid on a foundation 120 7 with an intervening fluidproof stratum 6.

125 In Fig. 4 is shown a modified arrangement, comprising a plurality of layers 1 with an intervening layer of fluidproof material such as roofing paper 16, laid on a foundation 7.

In Fig. 6 still another modification comprises a plurality of layers 1 of the stonelike concrete applied to a foundation 7 which has been provided with a plurality 130

of layers 66 of fluid-proofed material such as roofing paper, and these layers 1 may be applied by any suitable method, as for example, by superposition, one after the other, swabbing on layers or coats 61 of fluid-proof material such as asphaltum or pitch as the process progresses.

These illustrations are given merely by way of example of the various modes of 10 installing my improved veneer of stonelike concrete.

For example the layer 61 of cement shown in Fig. 2 may be of Portland cement or other cementitious substance applied in 15 plastic condition and waterproof but not necessarily flexible.

Having illustrated and described my invention thus fully, I wish it understood that I do not limit myself to the specific 20 materials and construction illustrated and described by way of example, nor in general do I limit myself otherwise than as set forth in the claims, read in connection with this specification.

25 What I claim as new, and desire to secure by Letters Patent of the United States of America, is:—

1. A portable covering of the class described; comprising a plurality of thin layers of heat-proof stonelike material; and an intervening layer of highly flexible, moisture-proof material secured to said layers physically and adhesively, said covering constituting a unitary heat-proof and

moisture-proof structure deformable transversely; substantially as described. 35

2. A covering device of the class described; comprising a plurality of layers of stonelike material; and an intervening layer of fibrous material treated with an oleaginous substance to form a flexible moisture-proof material; said layers being united to form a frangible structure retaining its heat-proof and moisture-proof qualities as a unitary structure after fracture, and capable of transportation and emplacement as a 40 unit. 45

3. A portable covering device of the class described; comprising a layer of burlap having monolithic layers of Portland cement molded on each surface, and permeated with asphalt of high melting point; substantially as described. 50

4. A flexible covering of the class described; said covering comprising a sheet of wear-resisting cement molded and cured on each side of a fabric and cross-scored on each surface to form tessellæ, and deformable longitudinally and laterally; constituting a stonelike unit emplaceable as such. 55

Signed at Newark in the county of Essex and State of New Jersey, this 23d day of February, 1912.

JAMES H. MUNRO.
